UNITED STATES PATENT OFFICE.

ADOLF BELER, OF PITTSBURGH, PENNSYLVANIA, ASSIGNOR TO TROOP MANUFACTURING COMPANY, OF PITTSBURGH, PENNSYLVANIA, A CORPORATION OF PENNSYLVANIA.

GAS BURNER.

1,420,405.

Specification of Letters Patent. Patented June 20, 1922.

Application filed August 25, 1919. Serial No. 319,588.

To all whom it may concern:

Be it known that I, ADOLF BELER, a citizen of the United States, residing at Pittsburgh, in the county of Allegheny and State 5 of Pennsylvania, have invented certain new and useful Improvements in Gas Burners, of which the following is a specification.

My invention relates to improvements in gas-burners, and particularly to a gas-burner 10 of the type particularly adapted for use in connection with water heaters, although the burner may be employed in connection with other structures.

Burner-plates heretofore employed in gas 15 burners of the type to which my invention relates have been made of very frail material, usually wire gauze, or very thin perforated plates, and considerable trouble has been caused by the employment of these 20 frail burner-plates, due to distortion caused by corrosion and heat acting upon this frail material, thereby permitting back-burning or back-firing.

An object of the present invention is to 25 provide a strong durable and efficient burner-plate for gas-burners of this class; a burner-plate of such a character as to prevent back-firing or flashing and one that may be readily applied to and removed from the 30 burner structure.

In the accompanying drawings which illustrate an application of my invention,

Fig. 1 is a front elevational view of a burner constructed in accordance with my 35 invention;

Fig. 2, a central vertical sectional view;

Fig. 3, a top plan view of the burner-plate; and

Fig. 4, a detail view showing the character 40 of the material employed in making the burner-plate.

Referring to the drawings, 1 designates the body of the burner; this body is hollow and is formed at its lower end with an open 45 flared portion having means 2 for engaging a gas supply pipe, not shown. Gas and air enter the lower end of the burner and are mixed in a passage 3 as is usual in this class of burners.

50 The upper portion of the body is enlarged to form an annular discharge chamber 4, the interior face of the wall forming said chamber 4 is provided with an annular shoulder or ledge 5, said shoulder being spaced a slight distance-inwardly from the

edge 6. Shoulder 5 provides a seat for the burner-plate hereinafter described.

Secured to the upper end of the body is a cap-plate 7; said cap-plate is formed with an annular face 8 designed to rest upon the annular edge or face of the body and is detachably secured thereto by bolts 9 passed through apertured lugs 10 and 11 formed respectively on the body and cap-members. The front wall of the cap-plate is extended laterally 60 at its upper end, as shown by the numeral 12, and this portion is provided with slots or passages 13 through which the products of combustion pass. The cap-plate, as illustrated, is formed with a forwardly projecting slightly inclined portion 14 located over and adjacent to the passages 13, and with rearwardly projecting portion 15 extending over and protecting the joint between the cap and body members. The construction 65 described forms an annular chamber 16 in the cap-plate, corresponding with the annular discharge member of the body.

A characteristic and important feature of the present invention is the burner-plate 17. 70 As illustrated and as preferred, this burner-plate includes a flat strip *a* of suitable material, such for example, as copper, brass or nickel, and a corrugated crimped or roughened strip *b* of similar material. These 75 strips are wound one upon the other to produce a circular structure having a great number of substantially uniform small orifices. The width of the strips should be sufficient to provide, when assembled, a body 80 of some thickness or depth. I find that such a body provides against back-firing or back-burning, and is of such a character 85 that it will not be distorted by heat and is strong and durable.

For maintaining the strips in assembled 90 position and for the purpose of positioning the burner-plate on its seat within the body member of the burner, I provide an open-work casing including a ring or band portion *c* having an upper annular outwardly projecting flange *d*, and a lower inwardly extending flange *e*, and a cross-member *f*. This band and cross-member are preferably 95 formed from a single piece of sheet metal. 100 Cross-member *f*, as shown, is made with an opening *g* through which a split rivet *h* extends.

Other means may be provided for maintaining the strips in assembled position from 110

those shown, and the strips may be differently arranged and more than two strips employed in forming the burner-plate without departing from my invention.

5 What I claim is:

In a gas burner, the combination with an air and gas mixing body-portion having a discharge chamber inclined thereto and formed with a circular wall opening, a de-

10 vice for preventing back-firing comprising a structure formed of flat and corrugated strips of metal wound upon each other to produce a circular structure, said structure disposed in said chamber and supported by

the circular wall, a cap-plate having a circular 15 bearing arranged in contact with the circular wall, a chamber inclined to the body-portion and a slotted laterally extending portion in advance of the chamber and the bearing, and means for securing the cap- 20 plate to the body-portion.

In testimony whereof I affix my signature in presence of two witnesses.

ADOLF BELER.
